UNITED STATES PATENT OFFICE.

JAMES B. ERWIN, OF MILWAUKEE, WISCONSIN.

COVER-WRENCH.

SPECIFICATION forming part of Letters Patent No. 700,752, dated May 27, 1902.

Application filed June 13, 1901. Serial No. 64,356. (No model.)

To all whom it may concern:

Be it known that I, JAMES B. ERWIN, a citizen of the United States, residing at Milwaukee, county of Milwaukee, and State of Wisconsin, have invented, new and useful Improvements in Cover-Wrenches, of which the following is a specification.

My invention relates to improvements in cover-wrenches for fruit-jars; and it pertains more especially, first, to the construction of the short arms of the clamping-levers, whereby as they are brought toward each other in the act of drawing the clamping-band around the cover the area of their contact-bearings against the clamping-band is increased and whereby the tendency of the clamping-levers to oscillate toward the right and left as the cover is screwed on and off is avoided, and, second, to the peculiar construction of the contact-bearing ends of the short arms of the clamping-levers; whereby they are adapted to partially surround the contact-bearings of the clamping-band, thereby preventing the clamping-band from turning upwardly and downwardly at right angles to the levers, as it might otherwise do when lifting the jar or when placing it upon the cover, and also whereby the ends of said short arms are prevented from coming in direct contact with the cover.

The construction of my invention is further explained by reference to the accompanying drawings, in which—

Figure 1 represents a plan view showing the wrench open preparatory to being placed upon the cover, and Fig. 2 is a like view showing the wrench in its closed position.

Like parts are identified by the same reference-letter in both views.

A A are the long arms, and B B are the short arms, of the clamping-levers, which are connected together by the pivotal bolt C.

D is a clamping-band. The band D is preferably formed of elastic steel wire the tension of which is such as to throw the operating-levers apart from each other when released from pressure, whereby said clamping-band is easily and quickly placed over the cover of the jar without the necessity of spreading the long arms of said levers. The short arms of the clamping-levers are provided with apertures E E for the reception of

the ends of the clamping-band D, while their ends are provided with concave grooves F F for the reception of the sides of the clamping-band. The respective ends of the clamping-band are inserted through the short arms of the clamping-levers from their inner opposing sides or edges, the ends of said clamping-band terminating outwardly, as shown, 55 whereby it is obvious that the contact-bearings of said clamping-band are brought within the grooves F F of said levers, and the ends of said levers are prevented from coming in direct contact with the cover, whereby 60 the liability of indenting the cover or breaking the jar is avoided. Attention is also called to the fact that the contact-bearing ends of said short arms are respectively curved outwardly and away from each other, whereby 65 as they are brought toward each other in the act of clamping the band around the can their contact-surfaces with the clamping-band are increased, so that when the levers are in the closed position their short arms afford 70 a broad bearing against said clamping-band, which prevents said clamping-levers from yielding or inclining toward the right and left, as they would otherwise do when screwing on and off the cover. Thus it will be obvious that by the peculiar construction of the 75 short arms of the levers and the peculiar manner of attaching the clamping-band three very important objects are accomplished. First, the clamping-band is so held that it can- 80 not be inclined upwardly and downwardly at right angles to the pivotal support when placing the same upon a cover or when lifting a jar; second, owing to the breadth of the contact-bearings of such clamping-arms they af- 85 ford a broad base for the clamping-levers by which they are prevented, as stated, from yielding toward the right and left when screwing on and off the cover, and, third, owing to the fact that said clamping-band is brought 90 within the grooved ends of the short arms of the clamping-levers said short arms are prevented from coming in contact with and injuring the cover when the same is being screwed on and off. It will be obvious that 95 by thus permitting the ends of the clamping-band to pass freely through the apertures in the short arms of the clamping-levers said band is free to be contracted to its smallest 100

diameter around the cover of the fruit-jar without changing its true circular form, as the surplus metal in the band when contracted to the smallest circle is free to pass toward the right and left through said apertures. It is also obvious that when the pressure upon the operating-levers is released the ends of the clamping-band will be drawn back through said apertures and the band will spring back 10 to its former position, describing a larger circle, while were the ends of said band prevented from thus passing through said apertures as the levers are drawn toward each other the clamping-band would be forced out 15 of its normal circular shape into an elliptical shape, and would not conform to the circular shape of the cover.

Having thus described my invention, what I claim as new, and desire to secure by Letters 20 Patent, is—

A cover-wrench for fruit-jars, comprising two pivotally-connected clamping-levers, having grooved, outwardly-diverging short arms provided with transverse apertures for the

reception of the ends of the clamping-band; 25 a circular clamping-band having its ends extending through, and slidably retained in, said apertures, and having intermediate portions thereof located in said grooves, whereby as said band is contracted around the 30 cover, the surplus portion of the ends in their contracted position is free to pass through said apertures and the band is permitted to close in a circular position around the cover, while at the same time the outer ends of said diverging short arms are brought into contact with 35 said clamping-band and the base of contact of said arms is increased, whereby the tendency of the same to incline in either direction, as the cover is turned, is avoided, substantially as set forth.

In testimony whereof I affix my signature in the presence of two witnesses.

JAMES B. ERWIN.
